UNITED STATES PATENT OFFICE

2,548,106

APPARATUS FOR MIXING AND DISPENSING PAINT

William L. Hancock and Bernard Walsh, Chicago, Ill., assignors to Martin-Senour Company, Chicago, Ill., a corporation of Ohio

Application December 30, 1947, Serial No. 794,718

4 Claims. (Cl. 259—67)

1

This invention relates to an apparatus for mixing and dispensing paints, whereby a predetermined hue, shade or tint can be accurately obtained and consistently reproduced within a particular color gamut.

A device of this nature is particularly useful not only in the field of interior decorating but any place where color harmony is an important consideration and where it is equally important that particular shades or tints are to be matched. In the field of selling paint, the retailer may be called upon to provide a wide variety of colors to meet the needs of his customers, and heretofore the only solution to this problem has been for the retailer to stock an uneconomical inventory of different colored paints which, more frequently than not, will not mix in the apparent direct proportions to produce the desired intermediate hues.

It is possible to produce an almost infinite number of shades and tints within a particular color gamut by utilizing a relatively few basic shading colors, preferably held to very close limits as to tinting strength, mass tone and weight per gallon. Certain of these basic shading colors may be mixed, for example, with a white base, an inert base and a mixing varnish in accordance with a predetermined formula, to produce a particular shade or color. The apparatus of the present invention has been devised to dispense accurate amounts by weight of certain basic colors to produce a predetermined shade or hue.

It has also been determined that the mixing of various colors by volume is inaccurate and does not always produce the desired shade. This is particularly true if a number of different colors are dispensed into the same container for mixing. The fault may lie not only in the variation of the tinting strength of different paints, but also in the containers themselves when the bottom of the container may not be uniform. In accordance with the present method, the various paints are adapted to be dispensed in such a way that a predetermined amount by weight of each color will accurately reproduce a desired hue.

It is, therefore, the principal object of the present invention to provide an apparatus for accurately dispensing and mixing predetermined amounts by weight of paints of certain colors in accordance with a known formula, to thereby produce a desired hue.

Another object of the invention is to produce an apparatus wherein a plurality of paint containers are mounted on a main frame and each container has a valve mechanism adapted to dis-

2

pense paint into a receiving receptacle where the paints may be mixed to form the desired hue.

Still another object of the invention is to provide an apparatus for mixing and dispensing paint wherein a carriage which has a weighing means embodied therein is adapted to be movably mounted on a main frame and to be moved adjacent a plurality of paint containers mounted on the frame, whereby paint may be dispensed from the various containers into a receptacle mounted on said carriage.

A further object of the invention is to provide a paint mixing and dispensing apparatus wherein a plurality of containers are mounted on a main frame, some of said containers being larger than others for the purpose of storing certain bases which may be used more often than any one of the base colors. It is preferable that the smaller containers be removably mounted on the frame so that they may be easily removed and refilled, the larger containers being preferably movably mounted on the frame by means which will enable such containers to be lowered on the frame for refilling.

25 A still further object of the invention is to provide an apparatus for mixing and dispensing paints wherein a plurality of containers are mounted on a main frame and a single driving means is adapted to drive agitators mounted within the containers for the purpose of agitating the paint therein and maintaining it always in a flowable condition.

Another object of the invention is to provide in an apparatus of the class herein described a novel 35 form of drive means for the agitators in a plurality of paint containers wherein detachable clutch means will permit the main drive shaft to rotate continuously and cause agitation of the paint in all of the containers even when one or 40 more of the containers has been removed for refilling.

Other objects and advantages of the invention will be apparent upon reading the following description taken in conjunction with the accompanying drawings in which:

Fig. 1 is a front elevational view of the apparatus with certain parts broken away for the sake of clearness;

Fig. 2 is an enlarged fragmentary vertical sectional view taken along the line 2—2 of Fig. 1;

Fig. 3 is a fragmentary vertical sectional view through the apparatus and taken along line 3—3 of Fig. 1;

55 Fig. 4 is a horizontal sectional view through one

of the containers and taken along the line 4-4 of Fig. 3;

Fig. 5 is a perspective view of one of the supporting brackets adapted to releasably support one of the small containers; and

Fig. 6 is a perspective view of one of the small containers showing particularly the base portion thereof.

The apparatus which has been designed for use in connection with the accurate dispensing of various colored paints to produce a predetermined hue or shade includes a main frame which has a plurality of paint containers mounted thereon. The containers which store main base colors may be made smaller than those which contain other ingredients used more frequently. For example, there may be anywhere from six to twelve small containers for storing the main base colors. The larger containers may be two or three in number, and preferably three, and may be used for example for storing a white base, an inert base and a mixing varnish. When a particular hue within a color gamut is desired, only a few of the colors stored in the smaller containers will be used, but usually a predetermined amount of each of the ingredients stored in the large containers will be used each time a color is mixed. Since these ingredients are used more frequently than any one of the paints in the smaller containers, it is advisable to have them stored in larger containers so that they will need refilling less frequently.

Any suitable form of main frame may be provided and may include spaced vertical end members 1 and 2 having a plurality of horizontal connecting angles 3. Suitable legs may be provided to rigidly support the entire frame. A horizontal angle member 4 extends between the upper ends of the end members 1 and 2 and an intermediate channel member 5 will extend between the end members 1 and 2 intermediate the ends thereof. A plurality of supporting brackets 6 are mounted on the channel member 5, each of which is adapted to support one of the smaller containers 7. The supporting brackets 6 include a novel form of construction whereby the paint container is not only supported thereon, but is locked against removal when the container is in its normal dispensing position.

A plurality of other supporting members 8 are movably mounted on the main frame structure, each of which supports 8 is adapted to receive one of the larger paint containers 9. Each of the smaller containers 7 is adapted to be completely removed from its support when the container is to be refilled, but the larger containers 9 being more unwieldy are not removed completely from the frame but are merely adapted to be lowered when they are to be refilled. The details of these structures will appear more fully hereinafter.

A driving means is located at any suitable point in proximity to the main frame for the purpose of forming a single drive means which actuates an agitator in each of the containers, both large and small. In the present and preferred embodiment of the invention a hood 10 extends forwardly from the upper angle 4 for the purpose of enclosing the operating mechanism for the agitators. A motor 11 may be mounted at approximately the center of the apparatus on the hood 10 and has a speed reducer 12 operatively connected thereto. The shaft 13 emerging from the speed reducer 12 has a sprocket wheel 14 mounted thereon to drive a chain 15 engaged therewith. The speed reducer 12, through the chain 15, drives another sprocket wheel 16 mounted on an elongated

drive shaft 17 extending throughout substantially the entire length of the main frame structure. The drive shaft 17 is located at the top of the frame and is mounted for rotation in suitable bearings affixed to the frame and positioned beneath the hood 10.

A plurality of bevel gears 18 are mounted in spaced relation on the shaft 17 for driving the agitators in the smaller containers 7, and a plurality of other bevel gears 19 are also mounted on the drive shaft 17 to actuate the agitators in the larger containers 9.

The structure of the driving means for each of the agitators in the smaller containers 7 is identical in each case and the details thereof are more clearly shown in Fig. 3. An arm 20 is suitably mounted on the main frame structure and extends horizontally forwardly terminating in a downwardly extending housing 21 adjacent the top of each of the containers 7. The housing 21 has a suitable opening therein to receive a stub shaft 22 within a bushing 23. The upper end of the shaft 22 is provided with a bevel gear 24 adapted to be in mesh with one of the bevel gears 18 on the drive shaft 17. The bottom end of the shaft 22 is provided with a clutch member 25 of any suitable form, but preferably of the form shown which will enable another and similar clutch member to be engaged or disengaged therewith. Any suitable form of agitator 26 may be located in each of the containers 7 and is such that the upper end thereof may be provided with a clutch member 27 adapted to be normally engaged with the clutch member 25. Thus, continuous operation of the motor 11 will, through the drive shaft 17, bevel gears 18 and 24, and the engaging clutch members 25 and 27, continuously drive and rotate the agitators 26 and continually stir the paint stored in the containers 7. This is necessary in order that the color of each of the paints in the containers 7 will be maintained uniform at all times and will be always in readiness for immediate dispensing and blending with other colors to form a predetermined hue within a color gamut.

The novel construction by means of which each of the containers 7 may be removably mounted on the main frame may be more clearly understood by reference to Figs. 3, 4, 5 and 6. Each container 7 consists mainly of a tubular member open at its bottom and adapted to be received by an annular ledge on a bottom member 28. The member 28 is preferably bowl shaped and is provided with two spaced radially outwardly extending locking lugs 29. Each of the lugs 29 has a downwardly depending flange 30 in spaced relation to the body of the bottom member 28.

Each bracket 6 includes a rear supporting plate 31 having suitable openings therein whereby the bracket may be attached to the channel member 5. A pair of spaced arms 32 are formed integral with the base 31 and extend forwardly therefrom. Each of the arms 32 terminates at its forward end in an arcuate receiving plate 33, the radius of curvature of such plates being substantially the same as that of the bottom member 28 so that said bottom member can be placed thereagainst and locked in position thereon. The rear face of each of the arcuate surfaces 33 is provided with an arcuate rib 34 extending in a horizontal plane thereby providing a ledge on its upper surface. When the container 7 and its bottom member 28 are in place on the supporting bracket 6, the lower sides of the arcuate flanges 30 will come to rest against the upper surface of the

ribs 34, and the upper edge of the arcuate faces 33 will be received by the space between the flanges 30 and the body of the member 28.

The arcuate length of each of the curved plates or surfaces 33 is substantially equal to the distance between the lugs 29. When the container 7 is removed for the purpose of refilling, the agitator 26 and its clutch 27 will be removed therewith. Obviously, it will not be possible to elevate the container 7 any higher than its normal operative position as shown in Fig. 3, because the clutch members will not permit such movement. Therefore, in assembling or replacing the container 7 on its supporting bracket 6, the procedure will be to place the container 7 in such a position that the lugs 29 thereon are below the curved faces 33. The container is then turned to bring one of the faces 33 in alignment with the space between the lugs 29. One of the lugs 29 will then also be in vertical alignment with the space between the arcuate faces 33. This will enable the container 7 to be moved vertically upwardly to a position where the two clutch members will be engaged and the upper edge of the faces 33 will be in horizontal alignment with the space between the flanges 30 and the body of the bottom member 28. The container may then be turned or rotated through an arc of a circle to a suitable position where the container will thereupon rest upon the ledges 34.

Suitable locking means are also provided to lock the container in place when it is in dispensing position. To the accomplishment of this end, there is provided a locking member which includes a plate 35 having outwardly extending ears 36 and a forwardly extending nose portion 37. Outwardly extending bosses 38 form bearings for a pintle 39, which in turn is supported at its ends in the vertically extending portions of the spaced arms 32. The pintle 39 permits a rotation of the plate 35 about a horizontal axis, and the ears 36 limit the rotative movement thereof in one direction by coming against the upper edges of the arms 32. The forward nose portion 37 is adapted to be located and positioned between the two lugs 29 on the container. When the container is to be removed or replaced, the plate 35 may be pivoted so that its nose portion 37 is moved upwardly. The container may thereupon be free to be rotated for attachment to or detachment from the supporting bracket. When the container 7 is in place for dispensing purposes, and the two lugs 29 are resting upon the forward ends of the arms 32, the space between the lugs 29 will be in vertical alignment with the space between the arms 32. The locking plate 35 may thereupon drop downwardly so that its nose portion 37 extends between the lugs 29. This nose portion 37 thereby forms a lock by preventing the container from being rotated to a position for removal.

It is to be noted that when the container is removed for refilling purposes, and the agitator and clutch connected therewith are also removed, the driving means for the other agitators continues to operate so that the paint in all of the other containers continues to be agitated and stirred even though one of the containers has been removed. Thus, there is an assurance that the paint in all of the containers will always be thoroughly blended and ready for dispensing regardless of the number of containers which have been removed for refilling.

Any suitable form of valve 40 may be attached to the bottom of each container 7 for dispensing

the paint contained therein. A preferred form of valve is disclosed in our copending application filed December 30, 1947, and bearing Serial No. 794,720, which valve is of the rotary type and is actuated by means of a handle 41. It will be obvious however that any other suitable form of valve can also be used in connection with the apparatus without in any way departing from the spirit of the invention.

The larger containers 9 present a slightly different problem because of their size which makes it more difficult for these containers to be removed for refilling. Accordingly, means have been provided whereby the larger containers can be merely lowered from their normal dispensing position for refilling purposes, and then elevated to their normal position. The construction and operation of this means together with the driving means for the agitators therein will be more clearly understood by reference to Fig. 2. Each of the larger containers 9 is provided with a cover assembly 42 at the top thereof, which cover has a vertical opening through the center thereof to receive a vertical shaft 43. The upper end of the shaft 43 is provided with a clutch member 44 adapted to be engaged with and disengaged from a similar and cooperating clutch member 45 mounted on the lower end of a shaft 46. The shaft 46 has a bevel gear 47 at its upper end in mesh with a bevel gear 48 on the drive shaft 17. In this connection it will be noted that the bevel gears 47 are preferably of a larger diameter than the bevel gears 24 which drive the agitators for the smaller containers. The reason for this is that the greater amount of relatively thick fluid in the larger containers requires that the agitation thereof be at a somewhat slower rate. The larger gears 47 will therefore drive the agitators in the larger containers at a somewhat slower rate of speed. The shaft 46 is mounted for rotation in a bearing or housing 49 extending downwardly from the forward end of a horizontal arm 49. The arm 49 is attached by any suitable means to a part of the main frame structure. The vertical shaft 43 has attached thereto a disc 50 below which the remainder of the shaft 43 extends as at 51 and is of a smaller diameter. The disc or member 50 has a plurality of outwardly and downwardly extending arms 52. An agitator 53 within the container 9 may be of any suitable form, but preferably includes a frame 54 having inwardly extending paddles 55 thereon. The top of the frame of the agitator 53 is provided with a plurality of openings 56 adapted to receive the downturned ends of the arms 52. The bottom of the agitator frame has a bearing member 57 adapted to be received in a suitable opening in the bottom 58 of the container whereby the agitator 53 may be rotated. A rotation of the clutch member 45 by means of the motor 11 and drive shaft 17, will actuate the clutch 44 and rotate the shaft 43 and member 50 connected thereto. The arms 52 will rotate and carry with them the agitator 53 whereby the paint within the container 9 will be continuously stirred. The cover 42 is preferably provided with an opening 59 normally closed by means of a hinged cover plate 60. Thus, when the container is lowered for refilling, the cover plate 60 may be raised and the paint or other liquid may be poured through the opening 59.

The bottom 58 of the container 9 is preferably in the form of a casting and has a rearwardly extending portion 61 integral therewith. There are also provided a pair of downwardly extending

tubular guide members 62. The member 61 has an opening 63 therethrough adapted to receive a screw 64 whereby it may be freely rotated. A large nut 65 is secured to the under side of the member 61 and is internally threaded to threadedly engage the screw 64. The lower end of the screw 64 extends downwardly through a bearing member 66 mounted on the horizontal portion of an angle member 67. The lower end of the screw 64 has a bevel gear 68 secured thereto in mesh with another bevel gear 69 mounted on the inner end of a forwardly extending shaft 70. The rear end of the shaft 70 is rotatably supported in a suitable bearing attached to the vertical leg of the angle 67. The forward end of the shaft 70 is rotatably mounted in a bearing 71 secured to a cross member 72 on the main frame structure. A handle 73 is affixed to the outer end of the shaft 70, so that the shaft 70 may be rotated to turn the screw 64 and cause the container 9 to be elevated or lowered. The two spaced tubular guide members 62 are adapted to receive guide rods 74 whereby the vertical movement of the container 9 may be effectively and easily accomplished.

Suitable valve means 75 having an actuating arm 76 thereon is affixed to the lower open face of the bottom 58. Here again, the valve 75 may be of any suitable form, but is preferably of the rotary type as disclosed in our above referred to copending application.

As has been explained hereinabove, it has been determined that more accurate results in the blending of paints to obtain a predetermined color can be obtained when predetermined amounts of the various paints are dispensed by weight in accordance with a known formula. To this end, a shelf 77 is provided on which may be located a pair of tracks 78. A carriage 79 is provided with suitable wheels 80 adapted to ride on the tracks 78 whereby the carriage may be moved from one end of the main frame structure to the other. The carriage 79 may be in the form of a weighing scale or may carry a weighing scale thereon. The form of this scale may be of any suitable type and forms no part of the present invention. The weighing scale will have suitable indicia 81 thereon to indicate the amount by weight of paint dispensed from each of the containers 7 and 9. The scale should be of such construction as to support a paint receiving container 82 thereon. The carriage or scale is located on the tracks so that it may be moved to various positions immediately below each of the containers 7 and 9. Again, any suitable means for holding the carriage and scale in position below each of the containers may be provided. Such holding means may be in the form of a brake attached to one of the wheels or may take the form of spaced detents 83 throughout the length of each of the tracks 78. If the detents are used, they should be spaced apart a distance equal to the distance between the wheels 80 as shown in Fig. 1, so that as the carriage is moved to a position below a certain container, the detents in the track will hold the carriage in that position while paint is being dispensed in the container 82.

It will therefore be evident that when a paint of a particular color or hue is to be mixed in accordance with a known formula, the carriage and scale 79 may start at one end of the tracks and will make stops below the particular containers storing the paint which is to be dispensed for the particular color desired. Usually the material contained in the larger containers

9 will be used for any desired color, although the proportions and weight of each ingredient may be varied. When the carriage supporting the paint receiving container 82 stops below any one of the containers 7 or 9, the valve associated therewith will be manually opened and the contents thereof dispensed into the container 82 until a predetermined weight thereof has been obtained. This procedure is followed throughout the entire formula so that at the completion of the process, an exact amount of paint of a desired color will be located in the paint receiving container 82.

Changes may be made in the form, construction and arrangement of parts from that disclosed herein without in any way departing from the spirit of the invention or sacrificing any of the attendant advantages thereof, provided, however, that such changes fall within the scope of the claims appended hereto.

The invention is hereby claimed as follows:

1. In an apparatus for mixing and dispensing paints, a main frame, a supporting bracket on said frame including two spaced outwardly extending arms terminating in arcuate portions adapted to receive and support a removable paint container, a removable paint container adapted to be received by said arms and be supported thereby, said container having radially extending lugs adapted to overlap said arms when rotated into dispensing position, and a pivoted releasable locking member mounted on said bracket, one end of said member being adapted to be received between said lugs on said container in dispensing position thereby to prevent rotation of said container.

2. A paint mixing and dispensing apparatus comprising a main frame, a plurality of stationary paint containers of varying size mounted thereon, gear means for driving agitators in said containers at different rates of speed, separable clutch means for detaching an agitator from said drive means, valve means at the bottom of said containers operable to dispense paint therefrom, a movable receiver supported on a movable carriage embodying weighing scales, a track mounted on said frame on which said carriage is adapted to travel to each of said stationary containers, some of said containers being removably supported on said frame by means of spaced lugs on said containers adapted to be received by cooperating spaced supporting brackets on said frame, and pivoted releasable locking members mounted on said brackets adapted to be received between the lugs on said removable containers in dispensing position to thereby prevent removal of said container from said brackets.

3. An apparatus for mixing paint comprising a framework, a plurality of stationary paint containers, mounted on said framework each adapted to contain and dispense paint of a different color in selected amounts, a track forming a part of said framework and extending beneath said stationary paint containers, a movable carriage embodying weighing means mounted on said track, and a traveling paint receiving container supported by said weighing means and movable with said carriage to receive an accurately determined amount by weight of paint from certain of said stationary containers in accordance with a known formula, whereby a predetermined hue within a color gamut may be readily obtained.

4. A paint mixing and dispensing apparatus comprising a main frame, a plurality of stationary paint containers mounted thereon, com-

mon means for driving agitators in said containers at different rates of speed, separable clutch means for detaching an agitator from said drive means, valve means at the bottom of said containers operable to dispense paint therefrom, a movable carriage embodying weighing scales, said scales being adapted to receive and support a removable paint container, a track mounted on said frame on which said carriage is mounted to travel to each of said stationary containers, some of said stationary containers being removably supported on said frame by means of spaced lugs on said containers adapted to be received by cooperating spaced supporting brackets on said frame, and pivoted releasable locking members mounted on said brackets adapted to be received between the lugs on said

removable containers in dispensing position to thereby prevent removal of said containers from said brackets.
